UNITED STATES PATENT OFFICE.

EDWIN L. GODING, OF PORTLAND, MAINE.

DESIGN FOR A SHOE.

SPECIFICATION forming part of Design No. 20,109, dated August 26, 1890.

Application filed April 29, 1890. Serial No. 349,958. Term of patent 3½ years.

To all whom it may concern:

Be it known that I, EDWIN L. GODING, a citizen of the United States, residing at Portland, in the county of Cumberland and State of Maine, have invented certain new and useful Improvements in Designs for Shoes; and I do hereby declare the following to be a full, clear, and exact description of the invention, such as will enable others skilled in the art 10 to which it appertains to make and use the same.

My invention relates to a new and original design for low shoes of the class known as "Oxford ties."

15 The accompanying drawing shows a shoe embodying my design. The quarter A is joined to the vamp B in such a way that the two together form what is termed in the trade a "slipper foxing"—that is to say, the upper

lines of the vamp and quarter are continuous 20 and form a nearly straight or slightly curved line from back to front. The gore-shaped top C is of a color which is in contrast with the color of the body of the shoe. The rear edge of the top is in the form of scallops c; or this 25 border may be otherwise ornamented.

The whole design is pleasing and attractive to the eye.

I claim—

The design for shoes herein shown and described. 30

In testimony whereof I affix my signature in presence of two witnesses.

EDWIN L. GODING.

Witnesses:

S. W. BATES,
E. T. FOLEY.
